CLAIM

The ornamental design for a housing for a microphone, as shown and described.

DESCRIPTION

FIG. 1 is a top, front and left side perspective view of a housing for a microphone showing our new design; FIG. 2 is a bottom side plan view thereof; FIG. 3 is a rear side elevational view thereof; and, FIG. 4 is a right side elevational view thereof, the left side elevational view thereof being a mirror image of the right side elevational view.

FIG. 1

FIG. 2

FIG. 3

FIG. 4
